UNITED STATES PATENT OFFICE.

JOHN Q. CLARKE, OF CRAWFORDSVILLE, INDIANA.

DESIGN FOR AN ANIMAL-TROUGH.

41,352.

Specification for Design.

Patented May 2, 1911.

Application filed September 29, 1910. Serial No. 584,584. Term of patent 7 years.

To all whom it may concern:

Be it known that I, JOHN Q. CLARKE, a citizen of the United States, residing at Crawfordsville, in the county of Montgomery and State of Indiana, have invented a new, original, and ornamental Design for an Animal-Trough, of which the following is a specification, reference being had to the accompanying drawing, forming part thereof.

The figure is a perspective view of the animal trough, showing my new design.

I claim:

The ornamental design for an animal trough, as shown.

JOHN Q. CLARKE.

Witnesses:

O. M. McLAUGHLIN,
G. H. BOINK.
